UNITED STATES PATENT OFFICE.

PETER BURD JAGGER, OF LONDON, ENGLAND, ASSIGNOR TO THE IMPROVED CONSTRUCTION COMPANY LIMITED, OF LONDON, ENGLAND.

MACHINE FOR MANUFACTURING CONCRETE ARTICLES.

1,142,522.

Specification of Letters Patent.

Patented June 8, 1915.

Original application filed February 20, 1907, Serial No. 358,418. Divided and this application filed September 13, 1907. Serial No. 392,742.

To all whom it may concern:

Be it known that I, PETER BURD JAGGER, a subject of His Majesty the King of Great Britain, residing at 47 Warwick road, 5 Maida Vale, London, in England, have invented certain new and useful Improvements in Machines for Manufacturing Concrete Slabs, Beams, Pipes, Tiles, and other Concrete Articles, of which the following is 10 a specification.

This invention relates to a new or improved machine for manufacturing concrete slabs, beams, pipes, tiles and other concrete articles which may either be reinforced or 15 unreinforced as desired.

In the ramming, pressing or jiggling processes for the manufacture of concrete slabs, etc., hitherto commercially used or proposed, the great difficulties presented are 20 the elimination of all air voids and excess moisture, and the obtaining of perfect density and solidification with even distribution of the material. Moreover for economical construction the greater the distribution of the mortar body by the use of 25 the larger aggregates the better, but there is limitation to this in the manufacture of concrete by hydraulic or other pressure machinery or by hand ramming, as it is impossible to compress with any economy unless 30 the aggregates are of a small uniform size.

With the machine according to my invention not only can all sizes of aggregates required for economy be used, but a steady 35 settling solidification of the material with even distribution of the aggregates is effected over all the surface of the table simultaneously, and all air voids and excess moisture are eliminated, and perfect density 40 and solidification obtained, the result being an article of great strength and durability.

With a machine according to my invention the plastic concrete (placed in molds suitable for articles to be produced) is supported upon a table capable of rocking about a horizontal axis and also of simultaneously moving substantially horizontally in a direction which traverses the plane of the rocking motion, means being provided 50 whereby a series of vertical blows are given to the supporting table preferably at the ends thereof. In other words, with a machine according to my invention, the directions of the horizontal motions or blows lie

in different vertical planes, as contradistinguished from cases where the directions of the horizontal motions or blows lie in the same plane.

I will describe with the aid of the accompanying drawings a construction of the machine which I have found to work well.

Of the drawings, Figures 1, 1^a Sheet 1 is a part side and part sectional elevation of the machine; Fig. 2 is an end view thereof; Fig. 3 Sheet 3, 3^a is a plan view of the machine with some of the mold boxes removed for disclosing the elevating tables, some of the latter being also removed for disclosing the guides therefor; Fig. 4 is a transverse section of the machine; Fig. 5, Sheet 5, is a 70 front view of an elastic eccentric rod head which I prefer to employ; Figs. 6 and 7 being sectional views of such elastic head taken respectively upon the lines X X and Y Y Fig. 5; Figs. 8 and 9 are respectively 75 front and side elevations of one of a pair of forked levers hereinafter referred to, while Fig. 10 is a detail view also to be hereinafter referred to.

Referring to Figs. 1-4, *a* designates a supporting frame preferably composed of a number of uprights and cross members. Between channel irons *b* *c* fixed to the central uprights and running transverse of the frame are fulcrumed at their lower ends a 80 pair of levers *d* *e*, which as shown in Figs. 8 and 9 are forked at their upper ends *f*. The ends *f* are provided with caps *g* and are bored to receive trunnions on blocks 16 which are bored to receive and support a shaft *j*. Upon the shaft *j* is centrally supported a 85 mold, table or platform *l* by means of bearings *h* secured to the depending sides *k* of the platform, table or mold. The levers *d* *e* are so located that the blocks 16 may bear 90 on their outer faces against the bearings *h*, and collars *h*¹ are provided on the shaft *j* as bearings for the inner faces of the trunnion blocks 16. Thus by rocking one or both of the levers *d*, *e*, through a small arc, 95 the table *l* is subjected to a substantially horizontal reciprocating motion while the table may be rocked about the shaft *j*, that is to say, in a vertical plane, the direction of which is at right angles to the direction 100 of the said reciprocating motion.

In order to provide means for rocking the levers *d* *e* and rocking the table *l* about the

shaft j lengthwise and preferably centrally of the frame a is journaled a shaft m suitably arranged to be driven from any available source of power. Upon the shaft are fixed at each end thereof eccentrics n and o . The eccentric n is connected to one of the forked levers (e) and the eccentric o is connected to one end of the table l for the purpose when the shaft m is rotated of simultaneously im-
10 parting a lateral reciprocating movement and a rocking motion to the table l .

The connection of either or both of the eccentrics n and o to the lever (e) and the table l may and preferably is arranged an
15 elastic one. As shown in Figs. 5, 6 and 7 and more particularly for the connection of the eccentric o to one end of the table l , I provide the eccentric rod p with a slotted head q , and in sliding engagement with such head
20 is arranged a bush r to which the table may be suitably attached. This bush r is normally held in position by springs $s s$, which at their one or inner ends bear against the bush and at their other or outer ends bear
25 against plates $t t$ also arranged in sliding engagement with the head q , so that by means of inclined cotter pins or wedges $u u$ they may be adjusted in position for varying the force of the springs $s s$, holes $v v$ being
30 formed in the wedges $u u$ and the plates $t t$ for receiving pins or the like for retaining the wedges when driven to the required position.

For the elastic connection of the eccentric
35 n with the lever e , I have found it convenient as shown in Fig. 4 to pass the head of the eccentric rod x through the lever and interpose springs $y y$ between the latter and adjusting screw nuts $z z$, although if de-
40 sired the form of elastic head described with reference to Figs. 5-7 may in this case also be adopted. The lever e may also be connected to the same eccentric as the lever e or it may be connected to an independent
45 eccentric.

At each end of the supporting frame as shown at the right hand side of Fig. 1 are arranged a number of preferably wooden concussion blocks 1^a , upon which the table
50 strikes as it is rocked, *i. e.*, a vertical blow is given to each end of the table alternately. For preventing any straining action upon the horizontal rod x , I prefer to set the eccentrics n and o upon the shaft m so that
55 the eccentric n will be crossing point of no travel when the table strikes against the blocks 1^a .

In addition to the vertical blows, side blows may also be imparted to the table l .
60 To effect this the table may be arranged to strike laterally against adjustable spring controlled rods or bolts 1^x carried by the supporting frame substantially as shown in Fig. 10.

65 To avoid any swiveling action of the table

this may be provided, as shown in Fig. 1, with a number of guide plates or the like 2 working in guides 3 fixed to the supporting frame.

In operation, the molds suitable for the 70 articles to be produced having been positioned upon the table l and filled with the plastic concrete material, rotary motion is imparted to the shaft m . This by means of the eccentrics n and o imparts an oscillatory 75 movement both to the lever e or levers $d e$ and the table l about their turning points. The table l is thereby simultaneously laterally reciprocated and rocked lengthwise of the machine, and a vertical blow is given 80 alternately at each end of the table by the alternate contact of said ends against the blocks 1^a . The shock thus imparted at each end of the table gives the desired vibration with the rocking and lateral reciprocating motion, and may be side blows also, keeps the longitudinal movement of the material steady.

By a machine constructed substantially as 90 hereinbefore described I am able to effect a steady settling solidification of the material over all the surface of the table, and not only are all air voids and excess moisture eliminated and stratification obviated, but 95 by the automatic adjustment of every particle of the material in its precise position, a maximum density of the material throughout is produced, without any pressure whatsoever, while moreover a great saving is at- 100 tained in the time required for the articles to thoroughly set ready for use.

It may here be observed that the provision of the elastic head to the eccentric rod or rods prevents or considerably reduces any 105 straining action upon the driving gear and allows the table to overrun and thus throw as much vibration to the center of the table as there is at the ends thereof.

As shown in the example of the machine 110 illustrated elevating gear may be provided beneath the supporting frame for lifting the concrete articles (where the shape of these permit) out of the mold boxes. A suitable arrangement of such gear consists 115 of plates 4 carried by rods 5 which work in brackets 6 connected to the frame a . The rods 5 are each provided with a rack 7 which is adapted to be operated by a pinion 8 fixed upon a spindle 9 and adapted to be rotated by a handle 10 (Fig. 2). The plates 4 have a number of upwardly extending fingers 11 adapted when the rods 5 are raised to pass through the bottom of the table l and the mold boxes 12 (in this case provided with removable plates 13 as false bottoms), and raise the plates 13 as shown in Figs. 1 and 2, so that for example a traveling trolley can be run over the table to pick up the plates with the formed articles there- 120 125 130

on, locking means such as ratchet wheels 14 and pawls 15 being provided to keep the rods 5 stationary as long as required.

As a modification, the table may be arranged at the ground level, so that a trolley or traveling support carrying the mold box or boxes may be run thereon, and such trolley or the like may be held on the table so that it has no movement independent of the latter, or it may be allowed a certain freedom to move backward and forward upon the table as this is operated as hereinbefore described.

I wish it understood I define the term concrete articles as those in which separate particles are formed into a mass or solid body.

Having thus described my invention, what I claim and desire to secure by patent is:—

1. A machine for purposes such as herein referred to, comprising a table, a horizontal pivot therefor, means for oscillating the table about such pivot, means for simultaneously reciprocating the table in the direction of the axis of such pivot, and means for arresting the oscillations of the table abruptly independently of the means producing the oscillations aforesaid.

2. A machine for purposes such as herein referred to, comprising a table, a horizontal pivot therefor, means for oscillating the table about such pivot, means for simultaneously reciprocating the table in the direction of the axis of such pivot, and means for arresting the reciprocations of the table in the direction of the axis of the oscillating pivot abruptly independently of the means producing the reciprocations aforesaid.

3. A machine for manufacturing concrete slabs, beams, pipes, tiles and other concrete articles, comprising a table, a supporting frame, forked levers pivoted to the support-

ing frame, trunnion blocks carried by such forked levers, a pivot shaft carried by the trunnion blocks and means attaching the table to the pivot shaft, the pivots of the forked levers being arranged to permit of movement of the levers in the plane containing the axis of the table pivot shaft aforesaid, a driving shaft, eccentric means driven by such shaft and adapted to impart movement to the forked levers so as to reciprocate the pivot shaft in the direction of its axis and other eccentric means connected to the table and adapted to oscillate the same about the axis of the pivot shaft when the latter is being reciprocated.

4. A machine for manufacturing concrete slabs, beams, pipes and other concrete articles, comprising a supporting table, a horizontal pivot therefor located intermediate of the ends of said table whereby said table may be oscillated about a horizontal axis, a rotary member, an eccentric member mounted on the rotary member and combined with said table for so oscillating the latter about the said axis, a second eccentric member mounted on the said rotary member and combined with said table for simultaneously imparting to the latter a substantially horizontal reciprocating movement in the direction of the axis of such pivot and stops against which the said table strikes as it is oscillated for imparting vertical shocks to said table substantially as described.

In testimony whereof I affix my signature in presence of two witnesses.
